CLAIM

The ornamental design for an anatomical cushion, as shown and described.

DESCRIPTION

1-3. Anatomical Cushion

The design of the anatomical cushion represents a sleeping and breathing trainer for a human, which is configured to subject the human to a natural breathing rhythm by laying against it, in order to sleep better.

1.1 is a perspective view of an anatomical cushion showing our new design;

1.2 is a side view thereof;

1.3 is a top view thereof;

2.1 is a perspective view of a portion of the anatomical cushion showing our new design;

2.2 is a side view thereof;

2.3 is a top view thereof;

3.1 is a perspective view of another portion of the anatomical cushion showing our new design;

3.2 is a side view thereof;

3.3 is a top view thereof.

(Continued)

The broken lines depict portions of the anatomical cushion that form no part of the claimed design.
